DELAY ACTION ELECTRIC DETONATOR

James Marchbanks Cooper, Ardrossan, Scotland,
assignor to Imperial Chemical Industries
Limited, a corporation of Great Britain

Application February 17, 1932, Serial No. 593,664
In Great Britain February 19, 1931

4 Claims. (Cl. 102—10)

When a delay action electric detonator functions, the following sequence of events is found: (1) The electric current from an exploder, or other source, fires the electric fuse; (2) the electric fuse fires the delay element, and (3) the delay element fires the detonator. It can be mentioned at this point that the delay element may consist of (a) a metal cylinder containing pressed delay composition; or (b) lead-covered fuse; or (c) lead semi-fuse; i. e. lead-covered fuse in which the powder core is covered with spinning and counteracting yarn, but with no waterproofing materials; or (d) compressed or moulded composition which is positioned in the detonator casing between the electric fuse and the detonator cap.

Between the electric fuse and the delay element there is always a gap or space provided with one or more vents to the exterior of the delay action detonator to allow for escape of combustion gases, the expansion of which would otherwise burst the casing. When the delay action detonator begins to function both hot combustion gases and flame are produced before the delay element has time to burn through to the material which is to initiate the surrounding explosive. Such gases and flame, if allowed to escape from the delay action detonator uncooled through the vents will be found invariably to ignite the explosives surrounding the detonator. If gunpowder happens to be the explosive in use then a premature explosion will occur.

According to the invention such premature ignition, or explosion, is prevented by masking the gas vent or vents by means of fine mesh, e. g. 80-mesh, wire gauze, or wire cloth. It is to be understood that the gauze or wire cloth only masks the vent holes, and does not prevent the gases from emerging therefrom. The wire gauze, or wire cloth, may be used either in the form of a strip of material wrapped outside the detonator and masking the gas vents externally, or it may be used in the form of a strip, or of a roll, or of a cylinder inside the detonator and masking the gas vents internally. A combination of the two methods may also be used, that is to say there may be a roll, strip, or cylinder of the wire gauze or wire cloth inside the delay action detonator masking the vents internally and a roll, strip or cylinder of such material masking the vents externally. Preferably the wrapping of wire gauze or wire cloth, whether used externally or internally, comprises several layers. In the case of the external wrapping it may be advantageous to make the same cover a relatively wide area of

the detonator surface, to afford increased opportunity for cooling of the gases should they tend to escape between the wrapping and the detonator casing. The delay action detonator can then be embedded entirely in any explosives without any risk of a premature ignition, or explosion, of the explosives occurring.

One example of my invention is illustrated more fully in the accompanying drawing in which Figure 1 is a sectional view in elevation of a detonator embracing the gas cooling means. Figure 2 is similar to Figure 1 but includes the spacing and gas cooling means on the outside of the detonator. Figure 3 is a view in cross-section of Figure 1, taken on a line through the exit opening, and Figure 4 is a like view of Figure 2. Fig. 5 illustrates a vertical section showing the application of gauze both inside and outside the tube, and, Fig. 6 shows a cross section of the same.

In Figure 1, A is the shell or container for the fulminate-chlorate or similar composition B, and C is the delay element comprising a metallic cylinder containing, for example, a pressed delay composition D. E is the upper part of the inner shell containing the electric fuse F, and connecting with the electric wires I, and G is the waterproofing composition or mixture for sealing the upper end of the detonator. H is an outer cylinder or metal tube having a friction fit with inner casings A and E to securely hold them in operative relation one with the other. The outer cylinder H has in its side wall an exit J for the escape of gases emanating from the delay element upon firing of the detonator. Inside of the cylinder H is an internal mask K positioned between the lower end of the electric fuse E and the upper end of the shell A, comprising a cylinder of wire gauze, which also functions as a spacing element between the upper and lower sections E and A of the detonator element.

In Figure 2 an external mask L is shown which not only acts as a cooling means for the gases escaping through the exit J, but spaces the heated portion of the detonator from the explosive in which the detonator is embedded.

Since the metal containers of the various elements of the complete delay action detonator are commonly made in friction fit pieces, the width of the wire gauze as in the above example can provide a convenient method of predetermining the distance between the electric fuse and the delay element. The detonator described in the above example is suitable for initiating black powder.

As many apparently widely different embodi-

ments of this invention may be made without departing from the spirit and scope thereof, it is to be understood that I do not limit myself to the specific embodiments thereof except as defined in the appended claims.

I claim:

1. A delay action electric detonator having gas escape means in the portion of the casing between the electric fuse and the delay element, and gas cooling means between said fuse and delay element, comprising a metal gauze.

2. A delay action electric detonator having gas escape means in the portion of the casing between the electric fuse and the delay element, and an internal cooling means holding said fuse and delay element in spaced relation, comprising a metal gauze.

3. A delay action electric detonator having gas

escape means in the portion of the casing between the electric fuse and the delay element, internal cooling means between said fuse and delay element and external wrappings of fine mesh wire gauze masking said gas escape means and capable of spacing the detonator from the explosive in which it is to be embedded.

4. A delay action electric detonator having gas escape means in the portion of the casing between the electric fuse and the delay element, and an external wrapping of fine mesh wire gauze masking said gas escape means and covering a relatively wide area of the detonator casing to space it from the explosive in which it is embedded and to accord increased opportunity for cooling of the gases should they tend to escape between the wrapping and the casing.

JAMES MARCHBANKS COOPER.
